UNITED STATES PATENT OFFICE.

LEO GIESE, OF FORT WORTH, TEXAS.

ALARM SYSTEM.

No. 922,883.

Specification of Letters Patent.

Patented May 25, 1909.

Application filed July 16, 1908. Serial No. 443,813.

To all whom it may concern:

Be it known that I, LEO GIESE, a citizen of the United States, and a resident of Fort Worth, in the county of Tarrant and State 5 of Texas, have invented a new and Improved Alarm System, of which the following is a full, clear, and exact description.

This invention relates to certain improvements in alarm systems, and more particularly to a circuit breaker adapted to operate upon a predetermined increase in temperature or upon being mechanically bent or broken.

The object of the invention is to so construct the device that the minimum quantity of fusible material need be employed, and so supported that upon being broken or fused, it becomes entirely displaced and the circuit broken.

Reference is to be had to the accompanying drawings, forming a part of this specification, in which similar characters of reference indicate corresponding parts in both the figures, and in which—

Figure 1 is a diagrammatic view of a system including my improved circuit breaker; and Fig. 2 is a vertical section through a circuit breaker constructed in accordance with my invention.

The specific form of circuit breaker illustrated in the accompanying drawing includes a tube 10 of copper or other heat-conducting material, and having means for subdividing it into two separate chambers 35 or compartments 11 and 12. This subdividing means preferably comprises a constricted portion 13, normally closed by a small plug 14 of wax or other substance of very low melting point. The lower compartment or chamber 12 is normally empty, while the upper compartment or chamber 11 is normally filled with mercury 15 or other liquid conductor. The upper compartment is hermetically closed by a plug 16 of hard

45 rubber or other solid insulating material, and two wires 17 and 18 extend through the solid plug into the mercury, their inner ends being amalgamated with mercury.

In a fire alarm system, I arrange a plurality of circuit closers at any and all points where it is desired to indicate the presence of

any dangerous increase in temperature. In Fig. 1, I have shown diagrammatically a system in which a plurality of the circuit closers are arranged in a battery circuit. A 55 wire 19 leads from a battery 20 through a suitable electromagnet 21 and thence through the several circuit breakers in series, back to the battery. For giving the alarm, I provide a bell 22, adapted to be operated by a spring motor, the motor being held from operating while a current flows through the electromagnet. As shown, the hammer 23 of the bell is provided with a slot 24, through which an eccentrically-mounted 60 pin 25 of a wheel 26 extends. The wheel is rotated by a spring motor, not shown, and in gear with the wheel 26 is a ratchet wheel 27. The armature 28 of the electromagnet is provided with a catch or dog for engagement with said ratchet wheel. The circuit flows continuously through the electromagnet and the terminals 17 and 18 and the mercury 15 of each of the circuit breakers, and the armature 28 is held in position to lock the 70 spring motor against operation. In case of any dangerous increase in temperature, the wax or other fusible plug of one or more of the circuit breakers will melt and the mercury will be permitted to flow out of the 75 chamber 11 down into the chamber 12. The breaking of the circuit between the terminals 17 and 18 will deenergize the electromagnet and the armature 28 will drop to permit the operation of the spring motor. The operation will be the same if the lower end of the tube be bent, twisted or jarred as the plug 14 is frangible when cold and is readily loosened so that it may drop into the lower compartment, even though the temperature be not 90 raised.

There is no necessity for more current than the minimum amount required to maintain the armature 28 in position. In order to save the current, I may, if desired, introduce 95 a resistance 29, whereby the current may be varied to suit the demands of the electromagnet and the strength of the battery.

Having thus described my invention, I claim as new and desire to secure by Letters 100 Patent:

In combination, a tube having a con-

stricted portion intermediate its ends, a fusible plug within said constricted portion and subdividing the tube into two compartments, mercury within the compartment
5 above the plug, and two electric terminals spaced apart and extending into one of said compartments.

In testimony whereof I have signed my name to this specification in the presence of two subscribing witnesses.

LEO GIESE.
